[57] CLAIM

The ornamental design for a video cassette package, as shown and described.

DESCRIPTION

FIG. 1 is a perspective view of a closed video cassette package showing our new design;

FIG. 2 is a perspective view thereof, shown in an opened position;

FIG. 3 is a perspective view thereof, shown in an opened position;

FIG. 4 is a perspective view of a first alternate embodiment of our new design, shown in an open position;

FIG. 5 is a front elevational view of the embodiment shown in FIG. 2; and,

FIG. 6 is a perspective view of a second alternative embodiment of our new design as shown in FIG. 2, the only difference being the decreased number and alternate position of the receptacle.

The undisclosed views of the videocassette package form no part of the claimed design.
